UNITED STATES PATENT OFFICE.

JENNIE REA KYLE, OF GEX, KENTUCKY.

SLEIGH.

SPECIFICATION forming part of Letters Patent No. 738,617, dated September 8, 1903.

Application filed June 8, 1903. Serial No. 160,561. (No model.)

To all whom it may concern:

Be it known that I, JENNIE REA KYLE, a citizen of the United States, residing at Gex, in the county of Gallatin and State of Kentucky, have made certain new and useful Improvements in Sleighs, of which the following is a specification.

My invention is an improvement in that class of sleighs which are formed of runners and hub attachments adapted for use in connection with a buggy or carriage body and its axles. Thus upon removing the wheels of a buggy or carriage from its axle-journals the latter may be inserted and secured in the hubs of my improved sleigh-runners.

The invention is embodied in the means for rigidly securing or locking the fifth-wheel of the buggy or carriage proper and the means for rigidly connecting and bracing the hubs of the runner attachment.

The details of construction, arrangement, and operation of parts are as hereinafter described, with reference to accompanying drawings, in which—

Figure 1 is a side view of a buggy-body, with axles and fifth-wheel connected with my improved runner attachment or form of sleigh. Fig. 2 is a plan view illustrating the attachment of my improved lock to the fifth-wheel of the buggy or carriage proper. Fig. 3 illustrates a modification in the arrangement of my improved lock. Fig. 4 is a vertical section illustrating a portion of my improved runner attachment. Fig. 5 is a vertical section on the line 5-5 of Fig. 2. Fig. 6 is a bottom plan view of the parts illustrated in Fig. 2. Fig. 7 is a vertical section on the line 7-7 of Fig. 2. Fig. 8 is a side view of my improved fifth-wheel lock, and Fig. 9 is a plan view illustrating the application of my improved lock to the fifth-wheel of a farm-wagon.

The buggy or carriage body A (see Fig. 1) is provided with a fifth-wheel B and with coupling poles or reaches C, which connect the front and rear axles D and E in the usual way.

My improved runner attachment consists of runners proper, F, and hubs G and a series of connecting-spokes H. The latter are attached and secured to the hubs G in the usual manner, as shown in Fig. 4, and their lower

ends may be turned out or flanged, as represented in Fig. 1, and secured by screws whose heads are countersunk in the shoes of the 55 runners F in the usual manner.

In order to rigidly connect and brace the hubs D and E, I employ a bar I, (see Figs. 1 and 4,) which may be constructed of steel or iron or wood and iron combined, the ends of 60 the same being bent downward and inserted in the hubs and secured therein practically in the same manner as the spokes H.

My improved means for locking the fifth-wheel consists of a curved bar K, having clips 65 or clamps k at its ends and an upwardly-projecting flange or lug k' at the middle of its length. When the device is applied, as shown in Figs. 1, 2, 5, 6, and 7, it is in rear of the bolster or head-block L of the front axle D. 70 Thus the clips k embrace the two parts of the fifth-wheel B and are clamped tightly thereto, while the flange or lug k' is secured to the bolster by means of a bolt k², as shown in Figs. 2 and 5. The clips k are formed by 75 means of two downwardly-projecting fingers or prongs, whose ends are screw-threaded, and a cross-piece k³, (see Figs. 2 and 8,) which is provided with two holes to receive the fingers, and is slideable vertically thereon, so 80 that it may be adjusted by means of the nuts applied to the fingers, as shown. It is obvious that by adjustment of the nuts the cross-piece k³ may be caused to clamp the two slideable parts of the fifth-wheel B to any required 85 degree, so as to hold them tightly or immovable. In place of arranging this improved lock K in rear of the bolster and axle it may be located in front thereof, as shown in Fig. 3, when the fifth-wheel B' is of the form that 90 requires such arrangement. In such case the curved arms of the device extend forward instead of rearward, and the clips are applied near the ends of the fifth-wheel. As indicated in Fig. 8, and also by shade-lines 95 in Figs. 2 and 3, the lock K is provided with depressions k⁴ in order to adapt it to the couplings or reaches C. In other words, the latter lie in the depressions k⁴, as indicated in Fig. 2. By means of this simple form of lock the fifth-wheel is locked so that the front axle is immovable, and thus all lateral pressure is removed from the runners F, so that they do not require to be connected or braced,

as has been usual in other attachments of this character. In brief, by means of this lock and the hub connections I, I form an improved attachment for a buggy-body or carriage, which is distinguished by lightness, strength, rigidity, and cheapness.

It will be understood that my improved lock will in practice be suitably modified to adapt it to different forms of fifth-wheels—
10 as, for example, to a farm or lumber wagon, as shown in Fig. 9.

Having thus described my invention, what I claim as new, and desire to secure by Letters Patent, is—

15 1. In a sleigh attachment for carriage-axles, the combination, with runners, hubs having vertical sockets in their upper sides, and spokes inserted in and radiating from the under side of the hubs, of the detachable ties and braces I, consisting of bars having their ends projecting downward at a right angle and entering said sockets, as shown and described.

20 2. The improved lock for a fifth-wheel, the same consisting of a curved bar having the upwardly-projecting flange at the middle of its length and screw-clips at its ends, substantially as shown and described.

25 3. The improved lock for the purpose specified, consisting of a bar having clips at its ends, which are adapted to embrace the fifth-wheel, and provided at its middle with a projection adapted to be secured to the bolster

of the buggy, substantially as shown and described.

35 4. The combination with the fifth-wheel and a bolster, of the improved lock comprising a bar having screw-clips at its ends, and a central lug, and a device securing the same to the bolster, substantially as shown and described.

40 5. The combination with the fifth-wheel, of the lock comprising a curved or arc-shaped bar having clips at its ends which embrace the fifth-wheel, and a central and upwardly-projecting lug, and a screw-bolt passing through the same and connecting it with the bolster, substantially as shown and described.

45 6. The combination, with the fifth-wheel, couplings or reaches, and a bolster, of the improved lock comprising a bar having depressions on each side of the middle, screw-clips at its ends, and a central lug, and a device for securing the latter to the bolster, substantially as shown and described.

50 7. The combination, with a fifth-wheel, and the bolster and front axle of a buggy or carriage, of the improved lock comprising a bar having clips arranged at its ends, and a central portion adapted to be secured to the bolster, and means for thus securing it, substantially as shown and described.

55 JENNIE REA KYLE.
